UNITED STATES PATENT OFFICE.

WILLIAM J. McCausland, of Philadelphia, Pennsylvania.

PRINTING-TELEGRAPH RECEIVER.

SPECIFICATION forming part of Letters Patent No. 339,312, dated April 6, 1886.

Application filed February 9, 1885. Serial No. 155,328. (No model.)

To all whom it may concern:

Be it known that I, WILLIAM J. McCausland, of the city and county of Philadelphia, and State of Pennsylvania, have invented a new and useful Improvement in Printing-Telegraphs, of which the following is a specification.

My invention has reference to printing-telegraphs; and it consists in certain improvements for driving the type-wheel in which a worm-wheel rotated by a mechanical motor revolves a worm-wheel fixed on the type-wheel shaft; further, in a unison controlled by the same electric current which operates the press-armature, the side unison being separate and distinct from the type-wheel or its shaft or the printing mechanism, and in many details of construction, all of which are fully set forth in the following specification and shown in the accompanying drawings, which form part thereof.

The object of my invention is to construct a positively and quicker mechanism for controlling and actuating the type-wheel of a printing-telegraph receiver, and is an improvement upon Letters Patent granted to me June 3, 1884, and numbered 299,664.

Figure 1 is a side elevation of a printing-telegraph receiver embodying my improvements. Fig. 2 is a front elevation of same. Fig. 3 is a perspective view of the electric motor which operates or rotates the motor-shaft.

A is a type-wheel shaft, A' is the type-wheel, B is a worm-wheel, C is the printing-armature, and D is the press-magnets, which are operated by an electric battery, X, from which the current is transmitted over the line-wire V, and the pulsations controlled by the key W or other suitable device.

F is the motor-shaft, and is provided with the worms E O, the former gearing with the worm-wheel B on the type-wheel shaft, and the latter gearing with the auxiliary worm-wheel P, having an independent shaft or bearing. The shaft F is provided with a crank, G, to which is pivoted or journaled the pitman H, hinged at its upper end to a pivoted bar, I, journaled at i, which bar is vibrated by a rod, K, and armature K', actuated by the elec-

tric magnet L. The spring J acts upon the bar I to draw the armature K' away from the electric magnets L and keep the crank G to the upper side of the shaft F.

To prevent the shaft F from stopping on 55 dead-center, it is furnished with the lugs M M, against which the pallets or arms N N press, being drawn against them by springs n n. The pallets n n and lugs M M insure the crank G passing sufficiently over the dead-centers 60 that, when the armature K' is drawn down by the electric magnets or is caused to rise by the action of the spring J, the rotation of said crank and its shaft F will always be in the same direction. This mechanism for driving 65 the shaft F is embodied in the patent herein-before referred to, and also in a pending application filed by me June 28, 1884. Therefore I do not claim this said construction in the application, and I would here remark that 70 while I prefer this motor for rotating the drive-shaft F, I wish it to be understood that it is immaterial to my invention how or in what manner the said shaft is rotated. The worm-wheel P has a finger, Q, which, as the 75 worm-wheel rotates, sweeps a given circle and makes one revolution with every revolution of the type-wheel, the worms O E and the worm-wheels P B being so proportioned that this result is attained.

R is a unison and armature-lever, and is actuated by an electro-magnet, U, located in the printing-magnet circuit V, so that every time the press-magnet is magnetized the unison-magnet is also magnetized. The upper end of 85 the armature-lever R is provided with a pivoted L-shaped piece, S, and pivoted to r and provided with the feet S', to allow of slight play in either direction, in the plane of the worm-wheel P, and normally is thrown forward toward the approaching finger Q by a small spring, T.

C' is a pivoted paper clamp-lever, and has its bottom roughened and its upper part provided with lugs C, between which the pin or lug e 95 on the press-lever C works, which in its upward movement rocks said lever C', so that its bottom is raised from off the paper D'. Now, as the press-lever C descends it forces the paper under the lever C', and just before coming 100

to rest the pin *c* strikes the other lug, *C'*, and presses the bottom of the lever *C'* down tight upon the paper, the said lever being held by friction or otherwise in either position it may be made to assume. The paper being now held by said clamping-lever *C'*, the next upward movement of the lever *C* causes more paper to be drawn off the reel and a fresh surface presented to the type-wheel.

10. The operation is as follows: As the shaft *F* is rotated it rotates the worm-wheels *B P* with uniform velocity, and may be so constructed that a semi-revolution or a complete revolution will cause the type-wheel to present a new letter on the printing-pad. In the unison which operates by the finger *Q* rotating around until it is arrested by the stop *S*, which it presses forward until the foot *S'* arrests it, then a further attempt at rotating the shaft *F* is prevented, thereby insuring the type-wheel to be brought to unison. Upon actuating the press-armature the armature-lever *R* will also be actuated, which action raises the piece *S* until it clears the finger *Q*, at which time the spring *T* forces it back to the rear of said finger *Q*, so that when the lever *R* is allowed to fall it no longer obstructs the movements of the finger *Q*, and hence the rotation of the type-wheel itself. It is self-evident that this unison might be used upon the machine in which the type-wheel shaft is driven by a spur-wheel and pinion, or both worm-wheels *B P* may be rotated by the same worm *E* directly, or indirectly by gearing the said worm-wheels together; therefore I do not limit myself to the details of the construction.

Having now described my invention, what I claim as new, and desire to secure by Letters Patent, is—

40. 1. A type-wheel provided with a worm-wheel secured thereto, in combination with a worm adapted to rotate said worm-wheel, substantially as and for the purpose specified.

2. A type-wheel provided with a worm-wheel secured thereto, in combination with a worm adapted to rotate said worm-wheel, and an electric motor to rotate said worm-wheel, substantially as and for the purpose specified.

45. 3. The combination of a type-wheel, a worm-wheel secured thereto, a worm adapted to rotate said worm-wheel, an electric motor to rotate said worm-wheel, and mechanism to overcome the dead-centers in the rotation of said worm, substantially as and for the purpose specified.

50. 4. In a printing-telegraph, a motor-shaft and a worm secured thereon, in combination with a worm-wheel provided with a pin or finger, an armature-lever having a catch to project into the path of said finger, and an electro-magnet adapted to actuate said armature, substantially as and for the purpose specified.

55. 5. In a printing-telegraph, a motor-shaft and a worm secured thereon, in combination with a worm-wheel provided with a pin or

finger, an armature-lever having a catch to project into the path of said finger, and an electro-magnet controlled by the printing-circuit, substantially as and for the purpose 70 specified.

6. In a printing-telegraph, a motor-shaft and a worm secured thereon, in combination with a worm-wheel provided with a pin or finger, an armature-lever having a movable 75 catch to project into the path of said finger and be pushed in one direction, a spring to throw said catch back to the other side of said finger upon its being freed therefrom, substantially as and for the purpose specified. 80

7. In a printing-telegraph, a type-wheel and a worm-wheel secured thereto, in combination with a worm and a unison device actuated by said worm, substantially as and for the purpose specified. 85

8. In a printing-telegraph, a motor-shaft and a worm secured thereon, in combination with a worm-wheel provided with a pin or finger, an armature-lever having a catch to project into the path of said finger, an electro-magnet to operate said armature, and gearing 90 to cause said worm-wheel to rotate synchronously with said type-wheel, substantially as and for the purpose specified.

9. The combination of type-wheel *A'*, shaft 95 *A* therefor, worm-wheel *B*, secured to said shaft, power-shaft worms *E O*, secured thereto, worm-wheel *P*, having finger *Q*, lever *R*, stop *S*, hinged to said lever, and magnet *U*, to actuate said lever, substantially as and for the 100 purpose specified.

10. The combination of type-wheel *A'*, shaft *A* therefor, worm-wheel *B*, secured to said shaft, power-shaft *F*, worms *E O*, secured thereto, worm-wheel *P*, having finger *Q*, lever *R*, 105 stop *S*, hinged to said lever and having feet *S'*, spring *T*, acting on said stop and magnet *U* to actuate said lever, substantially as and for the purpose specified.

11. The combination of power-shaft *F*, worm 110 *O*, secured thereto, worm-wheel *P*, having finger *Q*, lever *R*, having stop *S*, and electro-magnet *U*, to actuate said lever, the said stop arresting the rotation of the wheel *B* and its finger, substantially as and for the purpose 115 specified.

12. The combination of power-shaft *F*, worm *O*, secured thereto, worm-wheel *P*, having finger *Q*, lever *R*, having pivoted stop *S*, having feet *S'*, spring *T*, acting on said stop, and 120 electro-magnet *U*, to actuate said lever, the said stop arresting the rotation of the wheel *B* and its finger, substantially as and for the purpose specified.

13. The combination of shaft *F*, worm *O*, 125 worm-wheel *P*, lever *R*, having pivoted stop *S*, having feet *S'*, and spring *T*, substantially as and for the purpose specified.

14. The combination of pivoted press-lever *C* with paper-stop lever *C'*, adapted to be 130 rocked to clamp or unclamp the free end of paper by the said press-lever, according as it

is raised or allowed to fall, substantially as and for the purpose specified.

15. The combination of pivoted press-lever C, having pin c, with paper-stop lever C', having lugs C², adapted to clamp or unclamp the free end of paper with each movement of the press-lever, according as it is raised or allowed to fall, substantially as and for the purpose specified.

In testimony of which invention I hereunto set my hand.

WILLIAM J. McCausland.
